UNITED STATES PATENT OFFICE.

WILLIAM F. LERCH, OF HARTFORD, CONNECTICUT.

SWAB.

1,388,960.

Specification of Letters Patent. Patented Aug. 30, 1921.

Application filed April 22, 1920. Serial No. 375,776.

To all whom it may concern:

Be it known that I, WILLIAM F. LERCH, a citizen of the United States, and a resident of Hartford, in the county of Hartford and State of Connecticut, have invented a new and Improved Swab, of which the following is a full, clear, and exact description.

This invention relates to improvements in swabs, and more particularly to devices of the character stated designed for use in connection with iodin or any other liquid or fluid, or semi-fluid, an object of the invention being to provide a swab which will be entirely sanitary, which will permit the removal of the cotton after application, and which will result in a device which is entirely sanitary, and which most efficiently performs the functions for which it is intended.

20 A further object is to provide a swab with improved means for holding absorbent cotton on the end thereof, and which preferably forms a portion of a bottle stopper so that by manipulating the stopper, the latter operates as a handle for the swab.

With these and other objects in view the invention consists in certain novel features of construction, and combinations and arrangements of parts, as will be more fully hereinafter described and pointed out in the claims.

In the accompanying drawings—

Figure 1 is a view mainly in vertical section, but partly in elevation illustrating my invention.

Fig. 2 is a view in elevation of my improved swab removed from the bottle.

Figs. 3 and 4 are fragmentary sectional elevations illustrating modifications.

40 1 represents a bottle or container having a liquid 2 therein which we may assume to be iodin, although, of course, my invention is not limited to use in connection with any liquid or compound to be utilized.

45 3 represents the bottle stopper which may be of rubber, cork, or any other suitable material and to which a rod 4 is secured. This rod 4 is preferably of glass, although it may be made of any other suitable material and

50 is preferably secured in the stopper 3 by forcing the same into a recess 5 in the end of the stopper.

An enlargement 6 is provided on the lower end of the rod 4, and this enlargement, shown in Fig. 2, is of general spherical form. The enlargement 6 and the lower portion of

the rod 4 are made with a roughened surface 7 which may be conveniently formed by constructing the same of ground glass, although the roughened surface may be formed in other ways.

13 represents a ring which is movable on the rod 4, but which is of an internal diameter less than the external diameter of the enlargement 6 to prevent the accidental removal or loss of the ring.

In operation, absorbent cotton 8 is positioned around the enlargement 6 and the lower end of the rod 4 and the ring 13 is moved downwardly onto the cotton, clamping the same around the lower end of the rod so that the cotton is securely held and forms a part of the swab.

In Figs. 3 and 4, I illustrate modified shapes of the lower end of the rod and a modified form of clamping device.

In Fig. 3, the enlargement 9, corresponding to enlargement 6, is of ellipsoidal form and the clamping device is in the form of a conical ring or cup-shaped collar 10 which has an extended bearing or gripping surface against the cotton 8.

In the modification shown in Fig. 4, the enlarged lower end 11 of the rod tapers gradually, or, in other words, decreases in diameter from its lower end to its point of juncture with the main portion of the rod 4, and in this modification I have shown a slightly different shape of ring or collar 12.

It is, of course, to be understood that in some cases the cotton may be utilized in connection with the enlarged roughened end of the rod without the employment of any clamping device as the cotton will grip the rod, but, in most instances, I believe it advisable to employ a clamping ring or collar which will effectually secure the cotton to the rod.

With my improved device, after each operation the cotton can be burned or otherwise disposed of and the lower end of the rod and the ring can be sterilized before using again, so that the device can be maintained in absolutely sanitary condition at all times.

105 It should also be noted that the preferred form of the device might be employed without clamping cotton between the ring and rod as indicated in Fig. 2. When the swab is dipped into a bottle without any cotton around the enlargement, the ring will rest snugly against the enlargement and form a

dipper or container for liquid. When the enlargement is moved over the surface to be treated, the ring will be slightly displaced, allowing the liquid to leak between the ring 5 and the enlargement.

It is probable that the devices will be made comprising the stopper 3 and the elements of the swab and sold to the trade for use in connection with any sort of bottle or 10 container, or may be so manufactured as to be used without regard to the particular container.

Various other slight changes might be made in the general form and arrangement 15 of parts described without departing from the invention, and hence I do not limit myself to the precise details set forth, but consider myself at liberty to make such changes and alterations as fairly fall within the 20 spirit and scope of the appended claims.

I claim:

1. A swab, comprising a rod having an enlarged end adapted to receive absorbent cotton, and a ring movable on the rod and adapted to clamp said cotton on the rod, the 25 internal diameter of the ring being greater than the external diameter of the rod but less than the external diameter of said enlargement.

2. A swab comprising a rod, a handle on 30 one end of the rod, an integral enlargement on the other end of the rod, a ring movable on the rod between the handle and the enlargement, the internal diameter of said ring being greater than the external diameter of 35 said rod but less than the external diameter of said enlargement, and said enlargement tapering toward said rod and adapted to snugly accommodate the ring.

WILLIAM F. LERCH.
